UNITED STATES PATENT OFFICE.

CARA S. FERGUSON, OF COLUMBUS, OHIO, ASSIGNOR OF ONE-HALF TO I. LAWRENCE BROADWIN, OF NEW YORK, N. Y.

HOT-WATER BANDAGE.

1,238,901.

Specification of Letters Patent.

Patented Sept. 4, 1917.

Application filed December 13, 1916. Serial No. 136,601.

To all whom it may concern:

Be it known that I, CARA S. FERGUSON, a citizen of the United States, residing at Columbus, in the county of Franklin and 5 State of Ohio, have invented certain new and useful Improvements in Hot-Water Bandages, of which the following is a specification.

This invention relates to hot water bandages for external use by appliance directly to the body of the patient. Its prime purpose is to produce a bandage which may be made to supply the required heat to the afflicted part for a considerable time in a 10 manner similar in most respects to what is now known as hot water bottles. It will also be understood that, while I have termed my invention a hot water bandage, this term is used in the commonly accepted sense, although it is to be understood that the inverse is also true, that is, it may be used as an ice pack.

The main object of my invention resides in a structure wherein the flat shape may be 15 maintained after the bandage is inflated with the desired heating medium, the bandage being also constructed of material which gives it the desired degree of flexibility.

Still a further object of the invention resides in the combination of a flat flexible body of the type referred to, with a casing member and means whereby this casing and flexible body may be readily applied to the body of the patient.

Other objects of the invention will become more apparent from the following detailed description of the accompanying sheet of drawings, in which; similar characters of reference designate corresponding 20 parts, and in which:

Figure 1 is a view showing my improved type of bandage ready for application,

Fig. 2 is an enlarged detail view of the flexible flat body member which constitutes 25 one of the essential elements of my invention, and,

Fig. 3 is an enlarged section taken on line 3-3 of Fig. 1.

Referring to Figs. 2 and 3, there is shown 30 a flat flexible body 1, composed of two separate side walls inclosed at its lower end to thereby form a container, which container

is normally held closed by means of a removable stopper structure shown at 2. In order to maintain a flat appearance of the 55 element shown in Fig. 2, after the same has been filled with water or any other desired heating or cooling medium, I have so arranged my structure that the two side walls are tacked together at repeated intervals, so 60 that its inflation will not be accompanied by a corresponding distortion. This tacking of the side walls is accomplished by means of a plurality of longitudinally extending tubes 3 which may be either integrally 65 formed with the flexible body, or which are firmly secured thereto in any desired manner. As shown in the drawings, these tubes are open at their opposite ends so that the tubes, as well as the spaces between the tubes, 70 may be filled with water. After this element 1 has been filled to the desired extent with water, the stopper 2 is placed in a position of closure and the entire element then 75 incased within the tubular casing shown at 4. Usually this casing is made of cloth and its ends closed by means of the glove fastener arrangement shown at 5. One end carries a buckle structure shown at 6, while to the opposite end, there is rigidly secured 80 a strap 7, which strap is of the desired length and is provided with a plurality of apertures 8 for coöperation with the buckle 6, whereby the bandage may be applied and adjusted to the body as may be desired. 85 Should the length of the strap after its application, be too great, the end is fastened beneath the band shown at 9 in the usual manner.

From the foregoing description, it will 90 be apparent that I have provided a bandage which may be applied to any portion of the body of the patient, as may be desired. The body element 1 is made of rubber or other suitable material and is of itself very flexible. By means of the tube structure 3, this body is so formed that it will always maintain a flat appearance and, therefore, will much more readily conform to the contour 95 of the body.

What I claim, is:

A hot water bandage comprising a hollow body, a removable closure for said body, and a plurality of tubes extending longi-

tudinally of the interior of said body and attached to its opposite walls to hold them properly spaced when said body is filled, said tubes being open at their opposite ends 5 and of a length that their ends are also spaced from the ends of said body.

In testimony whereof I affix my signature in presence of two witnesses.

C. S. FERGUSON.
